Attorney, Agent, or Firm—St. Onge Steward Johnston & Reens

[57] CLAIM

The ornamental design for a telephone set, as shown and described.

DESCRIPTION

FIG. 1 is a front, top, right side perspective view of a wall mount telephone set showing my new design in cradled relationship, the left side being a substantially a mirror image of the right side, and with the rear and bottom sides of the stand being plain and unadorned; and

FIG. 2 is an associated view of the front elevation of the wall mounted stand, and a right side, bottom, and partial underside of the handset shown posted upon the top corner of the stand, the left side being a mirror image thereof.

FIG.1

FIG.2
